Primary Examiner — Michelle E. Wilson*Assistant Examiner* — Clese Moore, Jr.(74) *Attorney, Agent, or Firm* — SCHWEGMAN LUNDBERG & WOESSNER, P.A.(57) **CLAIM**

The ornamental design for a fairing for a vehicle as shown and described.

DESCRIPTION

FIG. 1 is a front perspective view showing the new design for a fairing for a vehicle;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The portions of the fairing shown in broken lines form no part of the claimed design.

1 Claim, 7 Drawing Sheets(56)
